UNITED STATES PATENT OFFICE.

ADOLPH C. RECKER, OF OAKVILLE, CONNECTICUT, ASSIGNOR TO WATERBURY MFG. CO., OF WATERBURY, CONNECTICUT, A CORPORATION.

PORABLE ELECTRIC LAMP.

1,225,491.

Specification of Letters Patent.

Patented May 8, 1917.

Application filed November 8, 1916. Serial No. 130,181.

To all whom it may concern:

Be it known that I, ADOLPH C. RECKER, a citizen of the United States, residing at Oakville, in the county of Litchfield and State of Connecticut, have invented a new and useful Improvement in Portable Electric Lamps; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a portable electric lamp embodying my invention.

Fig. 2 a view thereof in vertical section on the line 2—2 of Fig. 1, with a portion of the battery-casing in elevation.

Fig. 3 a view of the lamp in vertical section taken at a right angle to Fig. 2.

Fig. 4 a plan view of the candlestick with the battery casing removed therefrom.

Fig. 5 a plan view of the candlestick base. Fig. 6 a detached view of one of the modified forms which my rocking battery-lifter may assume.

My invention relates to an improved portable electric lamp, the object being to produce at a low cost for manufacture, a portable electric lamp constructed with particular reference to convenience and reliability of operation.

With these ends in view, my invention consists in a portable electric lamp having certain details of construction as will be hereinafter described and pointed out in the claims.

In carrying out my invention, I employ a candlestick, so called, comprising a struck up sheet-metal base 3 having a handle 4 and a flaring concentric socket 5 at the bottom of which is located a cup 6, the upstanding portion of which is threaded and its bottom portion formed with a concentric opening 7. Rivets 8 passing through the bottom of the socket 5 and through the bottom of the cup 6, secure the socket and cup to the base 3. A tubular casing 9 provided for the reception of a vertically movable battery 10, is formed at its lower end with threads adapting it to be screwed into the threaded upstanding portion of the cup 6. The upper end of the said casing is contracted and adapted to receive an incandescent lamp 11.

formed at its lower end with a contact 12 which is located directly above the terminal 13 of the battery 10. A helical spring 14 interposed between the upper end of the battery and the upper end of the casing, 60 provides for normally holding the battery in its depressed position.

For manually lifting the battery so as to light the lamp, I employ a rocking battery-lifter or switch consisting, as shown, of a single piece of wire having its outer end bent to form a finger-piece 15 arranged adjacent to the handle 4 and between the same and the socket 5. The said battery-lifter also comprises a straight stem 16 which rocks in a groove 17 formed in the circular flat upper face 18 of the central portion of the base 3, the said face forming a bearing for the socket 5 and receiving the rivets 8 aforesaid. The said stem 16 is bent about 75 midway of its length to form an eccentric, offsetting cam-like coil 19 for which clearance is made by corresponding registered openings 20 and 21 in the said face 18 and in the bottom of the socket 5. The coil 19 is arranged with respect to the finger-piece 15 so that when the same is in its vertical position as shown in Fig. 3, the coil is depressed so as to permit the battery to be pushed downward into its retired position 80 by the spring 14. On the other hand, when the finger-piece is turned horizontally, from left to right, as shown by broken lines in Fig. 4, the coil 19 rises through the opening 17 in the cup 6 and lifts the battery against the tension of the spring 14 so as to bring its terminal 13 into engagement with the contact 12 of the lamp 11, whereby the circuit is closed and the lamp lighted. When the finger-piece 13 is again lifted into its vertical position, the spring 14 re-asserts itself to depress the battery and put out the light. In the modified construction shown by Fig. 6, the battery-lifter comprises a finger-piece 22, a stem 23, and an arm-like loop 24 formed by bending the stem 23 transversely, the said loop having the same battery-lifting function as the coil 19 aforesaid.

I claim:—

1. In a portable electric lamp, the combination with a candlestick, of a tubular battery-casing carried thereby and adapted to have an incandescent lamp mounted in its upper end and to receive a vertically mov- 110

105

able battery, and a rocking battery-lifter journaled below the said battery-casing and formed between its ends with a lifting-member for lifting the battery within the said casing for closing the circuit through the lamp.

2. In a portable electric lamp, the combination with a candlestick, of a tubular battery-casing carried thereby, an electric lamp 10 mounted in the upper end of the said casing, a vertically movable battery located within the said casing, and a rocking battery-lifter mounted in the candlestick, having a finger-piece and formed with a stem provided with 15 an offsetting coil to engage with the lower end of the battery when the lifter is rocked for raising the battery to light the lamp, and for sustaining it in such position.

3. In a portable electric lamp, the combination with a candlestick comprising a base, 20 a handle therefor, a socket, and a threaded

cup located within the socket, of a tubular battery-casing having its lower end threaded for being screwed into the threaded portion of the said cup, an electric lamp located in the upper end of the said casing, a vertically movable battery located within the said casing, and a rocking battery-lifter interposed between the said base and the bottom of the said socket, and provided with a lifting-member arranged to engage with the lower end of the battery for lifting the same to light the lamp, and for sustaining it in its elevated position.

25 In testimony whereof, I have signed this 35 specification in the presence of two subscribing witnesses.

ADOLPH C. RECKER.
